UNITED STATES PATENT OFFICE.

MAXIMILIAN CHARLES SCHWEINERT, OF WEST HOBOKEN, NEW JERSEY.

LIFE-PRESERVER VALVE.

Application filed July 27, 1918. Serial No. 247,044.

To all whom it may concern:

Be it known that I, MAXIMILIAN CHARLES SCHWEINERT, a citizen of the United States, residing in West Hoboken, in the county of 5 Hudson and State of New Jersey, have invented certain new and useful Improvements in Life-Preserver Valves, of which the following is a specification.

This invention relates to life preserver 10 valves, and aims to provide certain improvements therein.

This type of valve is commonly used for inflating life preservers or similar devices. It usually comprises a barrel cemented or 15 otherwise secured to the fabric of the preserver, and a cap adapted to screw on the barrel for the purpose of holding the air in the preserver. No check in the barrel is usually provided since such devices are commonly inflated by the mouth and after inflation the finger is usually used to temporarily stop the flow of air out of the preserver while the cap is being adjusted. The cap, therefore, forms a necessary part for 25 the structure and it is important that such caps be secured against loss. The object of the present device is to provide a cap and its securing means which are of cheap and simple construction.

30 To this end I provide a cap which is of the type of pneumatic tire valve caps except that it has no screw-driver projections at the end of it, and this is secured against loss by a cord passing out of the top of the cap and connected to the latter by knotting it on the 35 interior of the cap. The cord is threaded in through the top, and a hole or holes is provided in the side of the cap projection through which the cord may be initially 40 threaded and knotted, after which the knotted end is drawn back through the hole so that it is housed within the projection.

Referring to the drawings which show the preferred form of the structure,—

45 Figure 1 is an elevation of the valve, showing the cap in place and the valve attached to a life preserver.

Fig. 2 is a vertical section of the cap on an enlarged scale.

50 Referring to the drawings, let A indicate the upper portion of a life preserver or other similar device, B the barrel of the valve and C the cap. The barrel is preferably notched or ribbed so that it may be firmly secured 55 to the neck D of the life preserver. The up-

per end of the barrel is commonly provided with a screw-thread E and the cap is interiorly screw-threaded as shown at F to fit the thread on the barrel. Within the cap is a rubber washer G which is preferably 60 dome-shaped and above the washer is a metallic disk H which permits the washer to rotate after its lower face comes in contact with the top of the barrel. This washer G closes the opening through the barrel so as to prevent the escape of air. J is a projection formed on the top of the cap which is provided with a hole or aperture K and at one or both sides of the projection are holes L. M is a cord or other flexible connection 65 which is secured at one end to the life preserver in any suitable way and at the other end is threaded through the hole K and knotted as shown, so that the cap is prevented from loss.

In securing the cord, the latter is passed down through the opening K and out through one of the openings L, and then knotted. After that it is drawn back through the opening L which is large enough to permit the knot to pass through it, until the latter is housed in the projection, the opening K being of smaller diameter and preventing the passage of the knot. One of the openings L facilitates the threading of the cord 80 through the opposite opening, since when the cord is passed downwardly through the opening K, a small instrument may be inserted through one opening L and the cord passed out through the other opening.

85 This makes a very cheap and simple connection and one which permits the usual manipulation of the cap in screwing and unscrewing, since the cord is centrally arranged, and is out of the way of the fingers during application and removal. Further the cord is not liable to become twisted, and the knot is concealed, so that the device is neat and symmetrical in appearance.

90 While I have described in detail the preferred form of the invention, it will be understood that I do not wish to be limited thereto, since various changes may be made therein without departing from the invention.

100 What I claim is:—

1. A cap for a valve or the like having a seat, and a hollow projection above said seat, and having a hole through the top of such projection, and a hole through the side there-

of, whereby a cord may be passed down through both holes and be knotted and drawn upwardly through the side hole.

2. A cap for valves or the like, having a seat, and a hollow projection above said seat, a hole through the top of such projection, and two oppositely arranged holes through the side thereof, whereby a cord may be passed down through the hole in the top of the projection, and through one of the side holes, and be knotted and drawn upwardly through such side hole.

3. The combination with an inflatable bag and a valve stem secured thereto, of a detachable cap for the stem, said cap comprising a tubular extension terminating in a portion of reduced diameter, said extension also having a hole passing laterally through its wall, and a cord passing through the end

of said extension and having a knot located 20 below said reduced portion of the extension, the lateral hole in said extension being adapted to permit said knot to pass through it, one end of said cord being connected to said bag.

4. A screw cap for closing the end of a valve stem, having a threaded portion, a tubular extension, a shoulder between the threaded portion and the tubular extension, and packing seated on said shoulder, the extension having an end opening for an attaching cord to pass through and a side opening large enough to permit the passage of a knot on the end of the attaching cord.

In witness whereof I have hereunto signed 35 my name.

MAXIMILIAN CHARLES SCHWEINERT.
